UNITED STATES PATENT OFFICE.

WILLIAM R. JEAVONS AND ARNOLD R. WHITTAKER, OF CLEVELAND, OHIO.

OVEN.

1,166,131.

Specification of Letters Patent. Patented Dec. 28, 1915.

Application filed August 1, 1913. Serial No. 782,453.

To all whom it may concern:

Be it known that we, WILLIAM R. JEAVONS and ARNOLD R. WHITTAKER, citizens of the United States, respectively residing at 5 Cleveland, in the county of Cuyahoga and State of Ohio, have invented a certain new and useful Improvement in Ovens, of which the following is a full, clear, and exact description, reference being had to the accompanying drawings.

This invention relates to ovens, and more particularly to means whereby the doors of ovens may be supported in open position.

While applicable to doors of other ovens, 15 the invention illustrated herein is shown as applied to the door of an oven for gas or oil stoves. In ordinary practice, the doors are supported in open position by means of chains, the chains being hooked at their 20 lower ends to the door and at their upper ends within the oven. Among the disadvantages arising from the use of these chains is that, in closing the door, they are liable to be deflected outwardly, catching between 25 the door and the oven and preventing the closing of the door. A further disadvantage is that the ends are liable to become unhooked.

The object of this invention is to provide 30 door supporting means which are not liable to the objections noted and which combine these attendant advantages with cheapness of construction and ease of assembling and disassembling.

Still further and more generally speaking 35 the invention may be defined as consisting of the combination of elements embodied in the claims hereto annexed and illustrated in the drawings forming part hereof, wherein,

Figure 1 shows a perspective view of the 40 front of an oven, the door being open and being supported in accordance with our invention; Fig. 2 represents a vertical sectional view through the oven shown in Fig. 45 1; Fig. 3 is a view, similar to Fig. 2, showing the positions of the parts when the door is closed; Fig. 4 is a detail in plan of the connection between the lower end of the door support and the door; Fig. 5 a detail in 50 perspective of the connection between the support and the oven top; and Fig. 6 a detail in section showing a modification of the connection between the door support and the oven.

Describing by reference characters the 55 various parts illustrated herein, 1 represents

the sides, 2 the front, and 3 the top of an oven of the gas or oil stove type, the oven disclosed herein being of the "knock down" type.

Pivoted to the front is the door 4, said door coöperating with the opening 5. The oven is preferably of sheet metal, and the opening 5 is defined by bending the metal inwardly, as shown at 6, and then outwardly, as shown at 7. Above the opening, the metal of the front is folded upon itself to produce inwardly projecting flanges 8 and 9, and the top 3 is removably applied to the sides and ends of the oven, its front end being supported in the space between the flanges 8 and 9. The oven top is of double wall construction and fits within the space between the flanges 8 and 9, its lining resting on the flange 8. The door 4 is also of double-wall construction, the lining which fits within the opening 5 being spaced from the peripheral portion 4^a of the door, said peripheral portion seating against the front face of the oven surrounding the opening 5. Recesses are provided in the lining at 4^b and 4^c for the door supporting clips and for the door closure, respectively, the door closure being indicated at 10. Angle clips are provided which form 85 a part of the door supporting means, each clip comprising each a base 11 and an angular extension 12. The clips are fastened to the door, within their respective recesses, by means of bolts 13 and nuts 14.

15 and 16 denote jointed rods or wires, the former having an eye 15^a at its lower end by which it is pivotally connected to the upper end of the angular extension 12 and having at its upper end a second eye 15^b 95 which receives a corresponding eye 16^a at the lower end of the rod or wire 16. The upper end of the rod or wire 16 is bent upwardly, as shown at 17, and extends through the flange 8, being bent into a hook 18. In 100 the preferred construction, the flanges 8 are bent downwardly where the hook extends through it, as shown at 18^a, thus affording sufficient clearance between the hook and the lining of the top 3 to enable the hook and the rod or wire 16 to swivel freely. As a modification, the lining of the top 3 may be embossed or bent upwardly, as shown at 3^a, to receive the hook 18 and permit the rod 16 105 to swing without interference—see Fig. 6. 110

It will be observed that the upper ends of the supporting rods or wires are closer to-

gether than their supporting clips 11, whereby the supporting rods or wires for the two sides of the oven converge from bottom to top. This is a desirable feature of our supporting means since, when the door is raised, the natural tendency of the wires or rods 16 is to move toward each other by gravity, and thus come more surely within the space defined by the oven opening 5. As the door 10 is closed, the upper rods or wires 16 swing on their pivots and the lower portions thereof drop by gravity within the door opening, carrying the upper ends of the lower wires or rods with them. The weight 15 of the lower rods or wires (being freely pivoted) contributes to this action. By this arrangement the blocking of the door by the supports is absolutely prevented. When chains are used, the quick 20 closing of the door frequently results in throwing a portion of the chain outwardly between the seating portion of the door and the oven front, whereby the closing of the door is prevented,—an objection which is 25 overcome by our construction.

It will be evident further that the construction herein shown prevents the unhooking of the lower ends of the supporting wires 15, while the arrangement of the flange 30 18 immediately beneath the lining of the top 3 prevents the similar unhooking of the upper ends of the rods or wires 16. In fact, it is necessary to remove the top before the wires 16 can be swung to unhooking position. It will be observed further that the bases 11 of the clips are extended some distance beyond the bolts which hold them to the oven door and that the lining of the door is so formed as to prevent the clips 35 40 from swiveling on the bolts. This insures the clips against swiveling or turning into a position that would interfere with the proper closing of the door.

Having thus described our invention, what 45 we claim is:—

1. The combination, with an oven, of a door therefor, angle clips connected to the door, a flange in the oven above the door opening thereof, a pair of rods or wires pivotally connected to said flange and having their upper portions offset and their lower portions adapted to project through the door opening when the door is opened, and rods or wires pivotally connected to the first mentioned rods or wires and to the said clips. 50 55

2. The combination, with an oven having an opening in the front wall thereof, an inwardly extending flange above said opening, and a top removably seated on said flange, of a pair of rods or wires having hooked upper ends extending through said flange, a pair of rods or wires pivotally connected to the lower ends of the first mentioned rods or wires, angle clips secured to the door, and a pivotal connection between the 60 65

lower ends of the last mentioned rods or wires and the angle clips.

3. The combination, with an oven having an opening in the front thereof, of a door pivoted beneath said opening, a pair of rods or wires pivotally connected to the door, a second pair of rods or wires pivotally connected to the upper ends of the first mentioned rods or wires and extending within the opening in the oven front and pivotally supported within said oven, the distance between the upper ends of the upper rods or wires being less than the distance between the lower ends of the lower rods or wires. 70 75

4. The combination, with an oven having an opening in its front and a pair of vertically spaced flanges above said opening, of a door pivoted beneath the opening, a pair of angle clips detachably secured to the door, a pair of jointed supports for said door, each support comprising a pair of pivotally connected rods or wires, one of said rods or wires being connected to one of said clips and the other rod or wire having a hooked end extending through the lower flange, the 90 distance between the upper ends of said supports being less than the distance between the lower ends thereof, and a top having a lining and removably supported between the flanges and resting upon the 95 lower flange.

5. The combination, with an oven having an opening in its front and a flange above said opening, of a door pivoted beneath the opening, a pair of jointed supports for said door, each support comprising a pair of pivotally connected rods or wires, one of said rods or wires being connected to the door and the other having a hooked end extending through the flange, and a top having a lining and removably supported upon the flange, there being a clearance space between the hook and the lining. 100 105

6. The combination, with an oven having an opening in its front and a flange above said opening, of a door pivoted beneath said opening, a pair of jointed supports for said door, each support comprising a pair of pivotally connected rods or wires, one of said rods or wires being connected to the door and the other having a hooked end extending through the flange, and a top having a lining and removably supported upon the flange, the flange being depressed about the point of connection of the rods or wires therewith to provide a clearance between the hooks and the lining. 110 115 120

7. The combination, with an oven having an opening in the front wall thereof and an inwardly extending flange above said opening, of a pair of rods or wires having their upper ends pivotally connected to said flange and having their upper portions offset, a pair of rods or wires pivotally connected to the lower ends of the first mentioned rods 125 130

or wires, angle clips secured to the door, and a pivotal connection between the lower ends of the last mentioned rods or wires and the angle clips, the distance between the upper ends of the upper rods or wires being less than the distance between the lower ends of the lower rods or wires.

In testimony whereof, we hereunto affix

our signatures in the presence of two witnesses.

WILLIAM R. JEAVONS.
ARNOLD R. WHITTAKER.
